APPARATUS FOR SHAPING MATERIALS

John J. Kowalewski, Bronx, N. Y., assignor to
Electrolux Corporation, Old Greenwich, Conn.,
a corporation of Delaware

Application May 19, 1949, Serial No. 94,204

7 Claims. (Cl. 153—68)

1

This invention relates to a machine for automatically shaping elongated work pieces, such as metal strip brush elements, into predetermined star-shaped or similarly conformed units. More particularly, it embraces a metal shaping device for strip brush elements wherein the metallic brush strip is press fitted into conformal contact with the surface contour of a star-wheel and held in close contact therewith until relatively permanently set, whereupon it is stripped from the star-wheel and emerges in the form of a continuous spiral comprising a plurality of convolutions each of which can be cut and mounted to make individual rotary brush units.

It is an object of this invention to provide a device for forming an elongated work piece such as a strip brush element into a continuous and helically shaped body from which single unit turns may be cut to form individual star-shaped brush elements suitable for attachment on a rotatable mounting head for floor, furniture, etc., polishing devices.

A further object is to provide an apparatus for making brush elements continuously and with a minimum of waste of the brush forming materials.

Still another object is to provide an easily operated automatic device for making rotary brush elements, a device operable by anyone having the customary skill of the conventionally trained production line industrial worker.

Still other and further objects will become apparent and otherwise suggest themselves to those skilled in the art upon reading the description of the invention herein given.

To this end the invention is particularly described herein as applied to the manufacture of rotary floor polishing brush units. However, it is to be understood that the examples given are merely illustrative and are not to be construed as limiting the invention.

The improvements and advantages of the present invention are more readily appreciated when considered in conjunction with the appended drawings forming a part of this description and in which:

Figure 1 is a front perspective view of the entire apparatus in assembled condition, showing one of the cam units broken away and displaced forwardly on a broken axial line in order to show detailed constructional features more clearly;

Figure 2 is an exploded view taken from the same position as Fig. 1 but somewhat enlarged and showing the relationship of the various internal constructional elements making up the device;

2

Figure 2a is a face plan view of the plow-like wedge means for spirally ejecting or lifting the crimped brush strip from the machine, taken on the line 2a—2a, Fig. 2;

Figure 3 is a front plan view of the apparatus with the cover plate, holding pawl, front cam unit, and brush lifting plate for the completed brush removed;

Figure 4 is a rear perspective view showing the gear train and relationship of the driving parts, the side plate being removed;

Figure 5 is a partial sectional view taken on the line 5—5 of Fig. 3 showing, however, all the dismantled parts in their proper orientation for actual operation.

Briefly, this invention contemplates, in one of its aspects, a method and apparatus for press fitting a metal strip brush element into reentrant portions or indentations cut in the periphery of a rotating template, i. e., star-wheel, with the aid of cylindrical brush shaping elements which are sequentially inserted, removed and reinserted into conformally cut indentations in the template while the latter is continuously rotated.

This invention is predicated on the utilization of the phenomenon of cold flow in metals. The apparatus embodies a work piece shaping wheel having indentations or reentrant portions into which the work piece in the form of a brush strip is press fitted and conformably cold pressed to assume the desired design, after which it is removed by being lifted outwardly in the form of a helical spirally shaped body in one continuous piece.

The particular embodiment of the reentrant type of brush shown in the drawings may be variously modified. In some brushes, a more acute bending may be desired, in others, fewer reentrant portions may be utilized. In any embodiment the particular shape of the structure adopted is determined by the purpose which the brush is designed to serve.

Referring now in more detail to the embodiment shown in the accompanying drawings, Fig. 1 and more especially to Fig. 4, the particular device therein illustrated comprises a side plate 15, Fig. 1, a front plate 16 and a rear plate 17, Fig. 4, with hollow cylindrical collars or separating pillars 18 mounted therebetween. The whole assembly is held together by bolts 19 which pass from the outer surface of the plates and through the hollow pillars 18, forming a strong supporting framework.

The various elements comprising the brush forming device are mounted by appropriate shafts bearinged in the respective front and rear plates.

3

Thus a drive shaft 20 bearinged in bracket 21 which is mounted on the rear of front plate 16 is driven through reduction gearing by an appropriate power source such as an electric motor (not shown) and has a worm gear 22 affixed to its inner end. Gear 22 operatively engages sprocket 24 affixed to shaft 25. Shaft 25 is bearinged in front and rear plates, 16 and 17, respectively, and has affixed on its front end, a pair of cam members 26, 27, Figs. 1 and 2, which actuate ram 28 through contacting rollers, 29 and 30, respectively, on pin 31 in a reciprocal motion along ram guides 32, 33.

A train of gears at the rear of plate 17 operates to rotate the brush forming elements in synchronism with the ram 28. Thus pinion 40 affixed to shaft 25 engages idler spur gear 42 affixed to shaft 43 which in turn engages gear 44 affixed to shaft 45 on the other end of which brush forming star-wheel 50, Fig. 2, is affixed. The completely formed brush element is shaped by forced conformal contact with the contour of star-wheel 50. The brush strip 100, Fig. 1, enters as a straight brush element through guide rolls 35 mounted on a freely rotatable pivot member 36 ahead of a reciprocating plunger or ram 28 operated in synchronism with the presentation of appropriately contoured reentrant portions 151, Fig. 2, of the star-wheel 50. In order that the retraction of the plunger 28 does not effect an accompanying return of the formed strip brush to its previous relatively straight shape, the plunger action is effected while providing for the insertion ahead of it of a roller element 2, Fig. 2, having a cylindrical surface conforming with a predetermined portion of the reentrant section 152 of the star-wheel, the brush being pinched between the two conforming surfaces. Pawl means 80, Fig. 5, is provided to maintain the roller 2 in position within the thus newly entered reentrant portion 152 of the star-wheel 50 and during the withdrawal or retraction of the plunger 28 and until the roller is advanced by the reentrant portion into contact with a fixed roller retaining guide member, namely the inner or concave surface of guide 52. Thus a predetermined portion of the brush piece under pressure is molded into a set and permanent shape conforming to the corresponding portion of the outer surface or contour of the star-wheel 50 contacted thereby.

After the star-wheel has advanced a sufficient distance to enable the formed brush to assume a permanent set and to eliminate any tendency of the formed brush element to lift off the surface of the contour wheel and partially reassume its former straight shape, the previously inserted roller brush forming elements must be removed one by one from their immediately associated reentrant portions of the star-wheel and returned for subsequent reinsertion into a new and subsequently presented reentrant position along the contoured surface of the star-wheel.

In order to effect the desired recurrent use of the cylindrical brush shaping elements, a number, i. e. fourteen (1 to 14, inclusive, see Figs. 2, 3) in all, of these cylindrical elements are used, at most three of which are retained at any one time in actual brush forming or brush shaping position within the arms or fingers of the star-wheel 50. The three brush shaping cylinders, 2, 3 and 4, Fig. 2, are caused to remain between their immediately adjacent arms of the star-wheel 50 by riding along the inner or concave side of guiding cam 52 for a predetermined portion of a revolution of the star-wheel 50. At the

4

end of their useful functioning, these cylindrical elements are lifted from their immediately associated reentrant portions of the star-wheel by means of extracting cam 51.

Cam 51 together with the convex side of inner guide 52 and the front facing plate 16 serves as a magazine for storage and conveyance of the cylindrical shaping elements around the convex surface of inner guide 52. It is through this conveying means that these cylindrical elements are led back one by one through the magazine to positions for synchronized sequential reinsertion into brush forming position and into alignment with a corresponding and subsequently presented reentrant portion of star-wheel 50.

In this device the shaped and formed brush strip continues in contact with the conforming surface of star-wheel 50 until it contacts brush lifting plate 55 at its lower cam portion 56 which latter extends behind the base portion 102, Fig. 2, of the completely formed and finally shaped portion of the finished brush, forcing it axially and laterally out of the path of the periphery of the star-wheel 50 and lifting it from the outer circumference of the star-wheel and out of the path of the newly presented portion of the incoming brush strip 100.

A pawl 80 fulcrumed on front plate 16 in hinge members 81 holds the inserted cylindrical members in location between a pair of arms or fingers of star-wheel 50 after the ram 28 positions them substantially into their appropriate reentrant positions, e. g., cylinder 2 in reentrant section 152, Fig. 2, and holds them in place until further rotation of the star-wheel 50 advances the inserted cylinder to ride on the inner concave face of guide member 52, as shown at 3. Pawl 80 renders unnecessary the provision of an excessively long cam surface whereby ram 28 is held in its most remotely advanced or cylinder holding position. Thus, using holding pawl 80, ram 28 can be retracted immediately and the high portion or dwell of cam surface 26 can thus be considerably shortened. Simultaneously the retraction of ram 28 leaves a space vacant for the subsequent insertion of the next cylinder, i. e. number 1, into the next reentrant portion, i. e. number 151, of star-wheel 50 and thus into brush shaping position ahead of ram 28. This also permits the advancement of the remaining cylinders through the magazine under the terminal pressure of the last extracted cylinder, i. e. number 4, at the end of its brush forming step.

In operation, a straight or similar strip type of brush blank 100 is inserted by one end thereof into the space between the pivoted guide rolls 35 and from this point the brush passes down between the outer contour of star-wheel 50 and a partially inserted cylinder, 2, Fig. 2. After the cylinder 2 is pressed home against the metallic brush backing 100, pinching the latter firmly into place within reentrant portion 152, the star-wheel 50 is rotated continuously until the entire brush strip has passed through the machine and is lifted out by cam 56. This results in the production of a spirally shaped continuously formed helix, each convolution of which may be subsequently cut and fitted together at the ends to form ample brush stock for a single rotary brush. Such a brush is suitable for mounting in a frame or similar carrying member for use as a floor polishing brush, a furniture polishing brush, and the like.

It is to be noted that although a five pointed or five unit type of brush is shown, by simply vary-

ing the contour of the star-wheel 50 and correspondingly varying the other brush forming elements, 1 to 14 inclusive, various other types and designs of rotary brush elements may be obtained, and in a manner similar to that described above. In any event, the completely formed brush comes off the contoured wheel as a helical structure from which individually circular-shaped brush elements are readily cut.

The extracting or ejector cam 51 guides the cylindrical rolls, i. e. 4 through 14, into a storage and conveyor magazine formed by the concave side of outer guide track 51 and the convex side of inner guide track 52 both of which tracks are fixedly mounted by machine screws 90 on the face of front plate 16. A cover plate 62 held in place by screws 91 is mounted over the two guide tracks and completes the enclosed magazine chamber through which the brush forming cylinders are conveyed back into position for reinsertion into the brush forming cycle of operations.

A pivoted set of bristle guide rolls 35 is provided. These guide rolls introduce the brush strip into the star-shaped forming wheel at the proper angle. The guide rolls pivoted at 36 enable the brush strip 100 to swing freely in accordance with the angle made by the forming edge of the star-wheel, thus making necessary one and only one bend in the brush stock.

The forming rolls, 1 to 14, contacting the brush in sequence keep the latter from springing or distorting back into any semblance of its former more straightened condition prior to insertion or passage over the star-shaped contoured wheel. By lifting the shaped brush up the incline of the stripping cam 56, a slight camber is given the brush which enables it to come off in a helical form 101 and thus lifts it free of the star-shaped wheel. Thus, from each strip, five, six or more individual rotary brushes may be made, depending on the length of the original straight brush strip 100.

The slight internal camber 58, Fig. 5, of the star-wheel together with the diminished size of the inner portion 59, Fig. 5, of the cylinder forming members 1 to 14 serves to hold the metallic portion 102 of the brush strip 100 firmly in place against the contoured surface of the star-shaped brush forming wheel 50. This structure insures an upright brush structure, unaccompanied by any excessively distorted edge effect or twisting of the brush bristles, thereby assuring an even distribution of load over the entire brushing surface when mounted for use.

The use of the holding pawl 80 for maintaining the newly inserted forming cylinder in its advanced position, see Fig. 5, makes possible the immediate return of the plunger or ram 28 from its most advanced position as in Fig. 5 to its lowermost dwell on the camming surface, thus speeding up the process of insertion of a new cylindrical element and thus accelerating the entire process. The slightly beveled lower edge 85, Fig. 2 of pawl 80 facilitates the insertion of the next cylindrical member, i. e. number 1, Fig. 2, by forcing pawl 80 outwards and compressing spring bias 86 against stop 87. Stud screw and lock nut 88 provide the means for adjusting the depth of insertion of pawl 80 within opening 89 in cover plate 62.

The embodiment of the invention illustrated in the drawings and described in detail has been adduced merely for the purposes of showing a

specific disclosure, the scope of which is to be limited solely by the appended claims.

What I claim is:

1. Apparatus for shaping elongated work pieces such as strip brush units into strips of serpentine form having a succession of reverse bends, comprising means having a surface contour including reentrant portions, elements conformal with predetermined parts of said reentrant portions, means for inserting said elements into conformal relation with the reentrant portions of said contoured means, means for moving the contoured means in timed relation with the means for inserting the elements into the reentrant portions, means for guiding a work piece in between the elements and the surface of the contoured means, means for removing the elements from the reentrant portions after the shaping of the work piece, and means for removing the formed work piece from the surface of the contoured means.

2. Apparatus for shaping elongated work pieces such as strip brush units into coils of reentrant form having a succession of reverse bends, comprising a wheel having a predetermined contour of star shape and including reentrant portions, elements conformal with said reentrant portions, means for inserting said elements into conformal relation with the reentrant portions of the wheel, means for rotating the wheel in timed relation with the means for inserting said elements into the reentrant portions of the wheel, means for guiding a work piece in between the elements and said reentrant portions, means for removing the elements from the reentrant portions after the shaping of the work piece, and means for lifting the formed work piece from the contour of the wheel.

3. Apparatus for shaping elongated work pieces such as strip brush units into coils of reentrant form having a succession of reverse bends, comprising a wheel having a predetermined contour of star shape and including reentrant portions, elements conformal with said reentrant portions, means for inserting said elements into conformal relation with the reentrant portions of the wheel, means for rotating the wheel in timed relation with the means for inserting said elements into the reentrant portions of the wheel, means for guiding a work piece in between the elements, and said reentrant portions, means for removing the elements from the reentrant portions after the shaping of the work piece, means for lifting the formed work piece from the contour of the wheel, and means for conveying the removed elements back into position for reinsertion into conformal relation with the reentrant portions of the wheel.

4. Apparatus for shaping elongated work pieces such as strip brush units into coils of reentrant form having a succession of reverse bends, comprising a wheel having a predetermined contour of star shape and including reentrant portions, elements conformal with said reentrant portions, means for inserting said elements into conformal relation with the reentrant portions of the wheel, means for holding said inserted elements in position while the inserting means is retracted for reception of a subsequent element, means for rotating the wheel in timed relation with the means for inserting said elements into the reentrant portions of the wheel, means for guiding a work piece in between the elements and said reentrant portions, means for removing the elements from the reentrant portions after the shaping of the work piece, and means for lifting the formed work piece from the contour of the wheel.

7

5. Apparatus for shaping elongated work pieces such as strip brush units into coils of reentrant form having a succession of reverse bends, comprising a wheel having a predetermined contour of star shape and including reentrant portions, elements conformal with said reentrant portions, means for inserting said elements into conformal relation with the reentrant portions of the wheel, pawl means for holding said inserted elements in position while the inserting means is retracted for reception of a subsequent element, a gear train for rotating the wheel in timed relation with the means for inserting said elements into the reentrant portions of the wheel, freely pivoted means for guiding a work piece in between the elements and said reentrant portions, means for removing the elements from the reentrant portions after the shaping of the work piece, and means for lifting the formed work piece from the contour of the wheel.

6. Apparatus for shaping elongated work pieces such as strip brush units into coils of reentrant form having a succession of reverse bends, comprising a wheel having a predetermined contour of star shape and including reentrant portions, elements conformal with said reentrant portions, means for inserting said elements into conformal relation with the reentrant portions of the wheel, eccentric cam means for actuating said element inserting means, pawl means for holding said inserted elements in position while the inserting means is retracted for reception of a subsequent element, means for rotating the wheel in timed relation with the means for inserting said elements into the reentrant portions of the wheel,

15

20

25

30

freely pivoted means for guiding a work piece in between the elements and said reentrant portions, means for removing the elements from the reentrant portions after the shaping of the work piece, and means for lifting the formed piece from the contour of the wheel.

7. Apparatus for shaping elongated work pieces such as strip brush units into coils of reentrant form having a succession of reverse bends, comprising, an oscillatory ram, a star-shaped wheel having reentrant portions and being mounted in cooperative association with the ram, an eccentric cam for moving the ram in timed relation with the reentrant portions of the wheel, a plurality of roller elements adapted for sequential insertion between the ram and the reentrant portions of the wheel, means for guiding a strip brush work piece in between the roller elements and the wheel, means for operating the eccentric cam whereby the ram is first moved in one direction and then in the reverse direction for forming the work piece against said wheel, and gear train means for rotating the eccentric in timed relation with said wheel.
